ASH TRAY

Philip John Evett, Austin, Tex.

Application January 6, 1956, Serial No. 39,638

Term of patent 3½ years

(Cl. D85—2)

FIG. 1.

FIG. 2.

I claim:

The ornamental design for an ash tray, as shown.
